UNITED STATES PATENT OFFICE

NATHAN D. KEITH, OF DEDHAM, MASSACHUSETTS, ASSIGNOR TO THE WEST END THREAD COMPANY, OF BOSTON, MASSACHUSETTS, A CORPORATION OF MASSACHUSETTS

SEWING MACHINE SHUTTLE

Application filed August 2, 1930. Serial No. 472,550.

This invention relates especially, although not exclusively, to rotary or oscillatory sewing machine shuttles of the discoidal type, such, for example, as those extensively employed in certain kinds of shoe sewing machines. In shuttles of this type the thread is usually wound upon a bobbin which is rotatably supported on a cylindrical post or stud projecting axially from the bottom or closed side of the shuttle. The bobbin is freely rotatable on the stud and there is nothing to prevent it from coming off except gravity and the direction of pull-off of the thread. In order to retain the bobbin more securely in the shuttle and at the same time apply a certain tension to the thread, various devices have been proposed. Some of these have been arranged to bear frictionally against the wall of the opening in the bobbin, but these devices have offered no positive resistance to the escape of the bobbin, while the frictional resistance against such escape is limited by the tension which can be applied to the thread. Other devices of this character as heretofore proposed have included positive catches for engaging over the outer face of the bobbin, thereby providing a positive lock but making it difficult to remove the bobbin when it is desired to replace the same.

The present invention has for its general objects to overcome the above difficulties and to provide means for securely retaining the thread in the shuttle under suitable tension while permitting ready separation of the parts when a renewal of the thread supply is necessary, and also to make it possible to do away with the bobbin altogether and readily secure a thread cop directly in the shuttle. These and other objects of the invention will best be understood from the following description of certain preferred embodiments thereof illustrated in the accompanying drawings, in which

Fig. 1 is a central or axial section of a shuttle embodying the invention,

Fig. 2 is a perspective view of the shuttle body per se,

Fig. 3 is a perspective view of a thread

cop adapted for use in the shuttle body shown in Fig. 2.

Fig. 4 is a detail perspective view of the thread supporting post,

Fig. 5 is a sectional perspective view of the thread carrying sleeve,

Fig. 6 is a fragmentary sectional view similar to Fig. 1 illustrating a modification.

Referring to Figs. 1 to 5, the shuttle body 15, which may be of any suitable or well known form, is provided with the usual central or axial thread supporting post 16 the inner end 17 of which is reduced in diameter and threaded into a suitably formed axial boss 18 on the bottom or closed side 60 of the shuttle body. The post 16 is provided with a transverse bore 19 to receive a spring pressed detent in the form of two balls 20 between which is interposed a spring 21, the ends of the bore being peened over or partly closed so as to hold the balls against escaping entirely while permitting them to project somewhat from the surface of the stud. The balls 20 engage an interior annular groove 22 formed intermediate the ends of a thread receiving sleeve or cap 23 adapted to telescope over and rotatably fit the post 16. Said sleeve or cap is also adapted to be forced into and held snugly within the central opening 24 of a thread cop 25, said sleeve having its inner end 26 tapered to facilitate such insertion, and is formed at its outer end with an exterior annular flange 70 75 80 85 90 95 100 27 to engage the outer face of the cop.

When the sleeve 23 is inserted within the opening 24 of the cop 25 and is then placed in position on the post 16, as shown in Fig. 1, the balls 20 will be spring pressed into the groove 22, thereby affording a frictional resistance to the turning of the sleeve on the post, depending upon the strength of the spring, and also providing a substantially positive lock for holding the cop in position while permitting the ready removal of the sleeve by the exertion of a reasonable amount of force when the thread is exhausted.

As shown in Fig. 6, the invention can also be applied to a thread carrying bobbin instead of to a thread cop directly as above described. In Fig. 6 the sleeve or hollow

hub 28 of the usual thread carrying bobbin 29 is provided intermediate its ends with an interior annular groove 30 similar to the groove 22 of the construction first described and adapted to receive the spring pressed balls 20 and to cooperate therewith in substantially the same manner.

Having thus described my invention, I claim:

- 10 1. In a sewing machine shuttle, in combination, a thread-supporting post, a thread-carrying sleeve adapted to telescope over and rotatably fit said post, said sleeve having intermediate its ends an interior annular groove, and said post having a transverse bore, balls seated in and projecting from the ends of said bore, and a spring interposed between said balls for pressing the same into engagement with said groove when said sleeve is in position on said post.
- 15 2. In a sewing machine shuttle, in combination, a thread-supporting post, a sleeve substantially fitting said post and having a tapered inner end adapted to be forced into the central opening of a thread cop and a flanged outer end adapted to engage the outer face of said cop, and cooperating detent means on said post and sleeve for yieldingly resisting both rotary and axial movement of the latter with respect to the former.
- 20 3. In a sewing machine shuttle, in combination, a thread-supporting post, a thread-carrying sleeve adapted to telescope over and rotatably fit said post, said sleeve having its inner end tapered, having at its outer end an exterior annular flange, and having intermediate its ends an interior annular groove, and a spring pressed detent carried by said post and engaging said groove when said sleeve is in position on said post.
- 25 40 4. In testimony whereof I affix my signature.

NATHAN D. KEITH.
